11 Claims. (Cl. 29—169.5)

This invention relates to a method and apparatus for automatically tuning mechanical frequency sources, especially vibrating reeds for use with musical instruments.

Mechanical frequency sources for musical instruments employing vibrating reeds consist generally of a sounding plate provided with rectangular openings above which the reeds are secured. Generally, the reeds must be tuned to a frequency tolerance of plus or minus one cent (one cent equals one hundredth half tone) which corresponds to a tolerance of plus or minus 6×10^{-4} cycles per second.

In the preparation of tone producers such as vibrating reeds which are milled or ground, such accuracy cannot be achieved. Therefore, the reeds are subjected to a subsequent tuning process generally accomplished in three operations. In the first two operations, which may be considered preliminary, the coarse errors are eliminated. The final tuning must occur within the instrument itself, since after the sounding reeds have been built into the instrument, additional frequency shifts may occur. The vibrating reeds of each sounding plate are thus pretuned and thereafter machine tuned while they are riveted onto the sounding plate and comparing their frequencies of vibration to a fixed or reference frequency. Such tuning can only be accomplished by highly skilled tuners having exceptionally accurate hearing and years of intensive training. Furthermore, if the vibrating reeds must be ground in the middle, the spring action and rigidity of the reed is reduced to the detriment of the reed's tonal quality.

Accordingly, the main object of this invention is to avoid the above mentioned disadvantages by providing a method and apparatus for automatically tuning frequency sources without requiring highly skilled manual assistance.

Another object is to provide apparatus for tuning a vibratory reed without reducing the rigidity thereof.

Still another object is to provide apparatus capable of increasing the production of tuned frequency sources.

Yet another object is to provide apparatus for producing tuned, mechanical frequency sources having generally improved tonal quality.

According to the invention, these objects are accomplished by resonating a reed riveted to a sounding plate, generating an electrical signal having a frequency proportional to the vibration of the reed, and comparing the signal with a reference frequency. Depending upon the frequency deviation of this signal from the reference frequency, an error signal is generated which activates, during predetermined intervals, a lifting arrangement adapted to move the free end of the reed against a rotating material removing tool such as a grinding wheel. These intervals may be determined by a switch which alternately conducts and blocks the passage of the error signal to the lifting arrangement. Consequently, the grinding means may be inhibited for a period during which the vibrating reeds may be vibrated at its new resonant frequency and again compared with the reference frequency. The process continues until the absence of an error signal indicates that the resonant frequency of the reed is equal to the reference frequency, at which point the reed is properly tuned.

As a further feature of the invention, the measuring and grinding intervals may be made dependent upon the magnitude of the deviation of the vibrating reed from the reference frequency, i.e. for higher frequency deviations a long grinding period is used, and when the magnitude of the error signals become small, the grinding intervals are decreased. In this manner it is possible to more accurately control the tuning process. For example, in the event an accuracy of two cents is required, the maximum grinding time, for one interval, when the reed frequency approaches the desired frequency, is not longer than that required for a two cent change. If it is desired to provide a completely automatic tuning process, the error signal generated in accordance with the invention may be used to measure the frequency of a reed in order to initiate a subsequent sorting process by which improperly tuned reeds may be rejected.

The manner in which these and other objects of the invention are accomplished will become more apparent with reference to the following specifications and drawings, wherein:

- FIG. 1 represents a block diagram of the invention;
 FIG. 2 is a schematic diagram of the control circuit of the invention; and
 FIG. 3 is a schematic diagram of a circuit which may be used for sorting the tuned reeds.

Referring now to FIG. 1, a conventional untuned reed 10 is shown fixed to a conventional sounding plate 11 by means of a rivet 12. As schematically illustrated, light from source 14 is focused by means of lens 15 onto a photocell 16. The system is arranged so that vibration of the reed will periodically interrupt the path of the light to photocell 16. Under such conditions, the photocell will produce an output voltage which fluctuates at the frequency of the vibrating reed. The reed may be caused to vibrate by any conventional means (not illustrated) such as a blow nozzle or the like.

The fluctuating signal from photocell 16 is then fed to a control circuit 18 which in turn develops an error signal to activate a lifting solenoid 19. Energization of lifting solenoid 19 is operative to force vertical rod 20 upwardly against reed 10 pushing the reed against a material removing tool such as grinding wheel 21 which is rotated as shown. When reed 10 is pushed against wheel 21 the light beam from source 14 is no longer interrupted, and after a predetermined interval, control circuit 18 deactivates solenoid 19 permitting reed 10 to fall to its initial position. The reed is caused to vibrate once again, and the process continues until the reed is properly tuned, at which time control circuit 18 can no longer generate an error signal.

As shown in FIG. 1, control circuit 18 includes an amplifier 26 operative to develop an alternating voltage at its output which is coupled to a tuned amplifier 28. The output of amplifier 28 is fed to a discriminator 30 which develops a D.C. error signal on its output X proportional to the frequency deviation between the resonant frequency of the reed and a fixed or reference frequency. The reference frequency is selected by properly tuning the resonant circuits of tuned amplifier 28 and discriminator 30. The error signal from discriminator 30 is fed to a switch 32 which is activated by a clock pulse generator 34. As will be explained below, clock pulse generator 34 has two outputs; one of which permits the measurement of the reed frequency while the other enables the above described grinding operation to take place. Thus, when a signal is present on the GRIND output of generator 34, switch 32 is enabled to pass the error signal from discriminator 30 to the lifting solenoid 19. When a signal is present on the MEASURE output of generator 34, switch 32 is inhibited to afford ample time to vibrate the reed and measure the resonant frequency thereof.

As a feature of the invention, a regulator 36 is coupled between discriminator 30 and clock pulse generator 34 to control the time of occurrence of the output pulse. Thus, as the output of discriminator 30 approaches zero, indicating that the reed is almost tuned, regulator 36 alters the period of generator 34, reducing the grinding periods to avoid the possibility that too much material might be removed from reed 10.

In FIG. 2 a schematic diagram of control circuit 18 is illustrated. The fluctuating signal across photocell 16, indicative of the resonant frequency of the untuned reed 10, is coupled through capacitor C1 to the input of a two-stage amplifier 40. The output of amplifier 40 is A.C. coupled through resistor R9 and capacitor C3 to a conventional double ended clipper or limiter, comprising diodes D1 and D2 and D.C. batteries B1 and B2 so that its output has an amplitude independent of the amplitude of the applied input pulse.

Pulses from amplifier 26 are then coupled to tuned amplifier 28 which includes pentode 42, capacitor C5 and transformer 44. The values of the capacitor and transformer mutual inductance are selected so that the amplifier will be tuned to the desired resonant frequency. The amplified alternating voltage from tuned amplifier 28 is applied through capacitor C6 to a discriminator 30 which generates a direct error voltage proportional to the frequency deviation of the reed from the desired reference level. The operation of such discriminators is old and well known and need not be discussed in detail. It is sufficient to note that tuned circuits L1, C8 and L2, C9 are tuned precisely to the desired reference frequency. If the input voltage to the discriminator from amplifier 28 has the same frequency as the reference, equal but opposite voltages are formed across output resistors R12 and R13 and the resultant output voltage at point X is zero. If the frequency of the vibrating reed is lower than the reference frequency, the voltage across resistors R12 and R13 will be unequal and the resultant voltage at point X will be negative. The greater the deviation from the reference frequency, the greater will be the magnitude of the voltage at point X. Similarly, if the reed should be vibrating at a frequency above the reference frequency, the voltage at point X will go positive.

The clock pulse generator 34 in this embodiment of the invention includes a multivibrator comprising triodes 49 and 50 and associated RC circuits R20, C12 and R23, C14. Multi-vibrators are common electronic oscillators in which the tubes alternately conduct for a period of time dependent upon their associated time constants. In the present case, since it is desired that the GRIND period be short compared to the MEASURE period, the above time constants may be adjusted so that tube 50 will conduct about ten times as long as does tube 49 during each cycle. For example, the MEASURE interval may be one second and the GRIND intervals one tenth of a second. A differential relay 51 in the cathode circuit of the multivibrator provides the GRIND or blocking outputs on the contact 54. When tube 50 is conducting and tube 49 is non-conducting the measuring phase is enabled and the error voltage from the discriminator is disconnected from switch 32. During the GRIND intervals, since tube 49 conducts and tube 50 is cut off, relay 51 closes contacts 52 and 54 coupling the error voltage at point X to the electronic switch 32.

Switch 32 includes a D.C. amplifier 56 which is biased into conduction during the MEASURE interval by voltage divider R28, R27, R26 and the positive bias on its grid through closed contacts 53 and 54. The output of amplifier 56 is coupled through cathode follower 58 to a thyratron 60 which energizes the lifting solenoid 19 if a negative error voltage is coupled to the control grid of amplifier 56 through contacts 52 and 54 during the GRINDING interval.

The regulator 36 comprises a bridge including resistors R45 and R47 in the upper branches, triodes 64 and 66 in

the lower branches, and relay 68 as the diagonal branch. The grid of triode 66 is coupled through resistor R49 to the error voltage at point X of discriminator 30. It will be recalled that the magnitude of the direct voltage at point X is dependent upon the frequency difference between the vibrating reed and the reference frequency. Accordingly, the bias on the triodes may be set so that when the negative voltage at point X rises to a predetermined level towards a value of zero, triode 66 starts to conduct and destroys the balance of the bridge. When the bridge is unbalanced, current flows through relay 68 in the diagonal branch, opening contacts 69 and 77 which effectively switches off capacitor C13 which is across capacitor C12 of the clock pulse multivibrator. This capacitance reduction changes the time constant of the multivibrator so that the GRIND period will be reduced to a period of time which would not permit material to be removed from the reed beyond the tolerance requirements.

The operation of the circuit is as follows. As reed 10 is caused to vibrate, it periodically interrupts the beam of light to photocell 16 which produces a fluctuating voltage having a frequency proportional to the resonant frequency of the untuned reed. The fluctuating voltage from photocell 16 is A.C. coupled through the double stage amplifier 40 to limiter D1, D2 from which a voltage is obtained having a frequency identical to that of the vibrating reed and an amplitude independent of the input voltage. This voltage is then amplified by tuned amplifier 28 and coupled to discriminator 30 which produces a negative output voltage at point X having a magnitude indicative of the difference in frequency between the vibrating reed and the fixed reference frequency.

When multivibrator 49, 50 switches states, connecting contacts 52 and 54, the negative error voltage is coupled to D.C. amplifier 56 driving the tube to cut-off. With tube 56 cut-off, the voltage on the plate of tube 56 goes positive causing cathode follower 58 to conduct. The cathode of tube 58 is coupled through resistor R30 to the grid of thyratron 60, so that as tube 58 starts conducting and the voltage on its cathode goes positive, thyratron 60 starts to conduct. When thyratron 60 ignites, it energizes solenoid 19 which presses reed 10 against grinding wheel 21 as explained above in connection with FIG. 1.

Since reed 10 does not vibrate during the GRIND interval, the light ray is not interrupted at this time, and the voltage at point X rises toward zero depending upon the time constant of C10, R12 and R13. The GRIND phase is ended when multivibrator 49, 50 changes states causing relay 51 to apply a positive voltage to the grid of amplifier 56 through contacts 53 and 54 so that this tube again conducts. When the plate voltage of amplifier 56 drops, tube 58 is biased to cut-off causing the grid of thyratron 60 to go negative with respect to its cathode stopping conduction to solenoid 19. Once again, an error voltage at point X is formed so that the process may continue until the resonant frequency of the reed corresponds to the preset reference frequency. When this frequency has been obtained, no voltage is formed at point X, thyratron 60 cannot be fired, and the solenoid is not energized to push the reed against the grinding wheel. As previously described, regulator 36 is operative when the frequency deviations are small to change the time constant of the multivibrator so that the grinding interval will not last long enough to exceed tolerance limits.

It should also be noted that in the event the resonant frequency of the reed is above the reference frequency, the voltage at point X goes positive and thyratron 60 cannot be fired to actuate the lifting mechanism.

FIG. 3 illustrates a circuit which may be used to measure and sort the reeds after they have been tuned. The first part of this circuit, shown in block form, is identical to FIG. 2, and derives the error voltage from discriminator 30 in the same manner. In addition, this circuit includes a multivibrator 49', 50', D.C. amplifier 56', cath-

ode follower 58' and thyratron 60' which also operate in a manner similar to that described above.

The error voltage from point X is fed to a vibrator 70 which produces a pulsating direct voltage on its output line 72. This pulsating signal is converted to A.C. by capacitor C16 and thereafter clipped by diode D3 so that only a negative voltage is applied through contact 52' of relay 51' to the grid of D.C. amplifier 56'. Conduction of amplifier 56' causes thyratron 60' to fire as described above to energize a solenoid 74 which activates a drop pivot (not shown) to insert the reed being tested into a reject container. Simultaneously, the voltage on the output of cathode follower 58' is coupled to a second thyratron 78 and an RC circuit comprising capacitor C18 and resistor R35. The time constant of this circuit may be adjusted so that if a given number of consecutive deviations occur, capacitor C18 will be charged to a voltage sufficient to fire thyratron 78. Ignition of thyratron 78 causes relay 80 to open its contacts 82 and 84 which may be adapted in an obvious manner to open the voltage supply and put the entire circuit out of commission. If desired, relay contacts 82 and 84 may also be included in a circuit which will give a signal when the system is shut down. Since thyratron 78 is driven by direct current, the tubes will remain ignited even after the grid voltage is decreased, and the tube can only be extinguished by interrupting its anode voltage by means of switch 86.

At very low frequencies, it is difficult to achieve high circuit efficiency for the resonant circuits L1, C8 and L2, C9 of discriminator 30. In such a case, a conventional frequency multiplier may be inserted between photocell 16 and capacitor C1 of the input to amplifier 40. In this manner, the circuit may be tuned to a given multiple of the desired frequency and operated at the higher frequency.

In addition, various means may be used to detect the frequency of vibration of the reed other than the photoelectric means disclosed. Many other modifications of the invention will also be obvious to one skilled in the art, and the invention should not be limited except as defined in the following claims.

I claim:

1. Apparatus for tuning a mechanical frequency source, comprising means for vibrating said source, means for generating an electrical signal having a frequency proportional to the frequency of vibration of said source, means for generating an error signal proportional to the difference in frequency between said signal and a predetermined frequency, and means responsive to said error signal for changing the physical dimensions of said source in order to vary the resonant frequency thereof.

2. Apparatus for tuning a mechanical frequency source according to claim 1 including timing means for enabling said dimension changing means only during predetermined time intervals.

3. Apparatus for tuning a mechanical frequency source according to claim 2, including regulating means for decreasing the length of said time intervals when the resonant frequency of the source approaches said predetermined frequency.

4. Apparatus for tuning a vibratory reed, comprising means for vibrating said reed, means for generating an

electrical signal having a frequency proportional to the frequency of vibrations of said reed, timing means, means responsive to said timing means for generating an error signal during a predetermined time interval, said error signal being proportional to the difference in frequency between said signal and a predetermined frequency, grinding means, and means responsive to said error signals for bringing said grinding means into contact with said reed during predetermined time intervals in order to raise the resonant frequency of said reed.

5. Apparatus for tuning a vibratory reed according to claim 4 including regulator means for varying said last named time intervals when the resonant frequency of the reed approaches the predetermined frequency.

6. Apparatus for tuning a vibratory reed according to claim 5 wherein said generating means includes light generating means and photoelectric sensing means responsive to the interruption of said light beam by said vibrating reed.

7. Apparatus for tuning a vibratory reed according to claim 6 wherein said generating means includes a tuned amplifier and a discriminator for producing an error voltage proportional to the difference in frequency between the vibrating reed and said predetermined frequency.

8. Apparatus for tuning a vibratory reed according to claim 7 wherein said regulator means comprises a multivibrator and means for changing the time constant of said multivibrator depending upon the magnitude of said error voltage.

9. A process for tuning a mechanical frequency source, comprising causing said source to vibrate at its resonant frequency and thereafter generating an electrical signal proportional to the difference in frequency between said vibrating source and a predetermined frequency, changing

35 the physical dimensions of said source during predetermined intervals under the control of said error signal, remeasuring the resonant frequency of said source and continuing the process until the resonant frequency of said source is equal to said predetermined frequency.

10. A process for tuning a mechanical frequency source according to claim 9 including the step of altering the time interval during which the physical dimensions of the source are changed when the resonant frequency of the source approaches said predetermined frequency.

11. Apparatus for testing and sorting a mechanical frequency source, comprising means for vibrating said source, means for generating an electrical signal having a frequency proportional to the frequency of vibration of said source, means responsive during fixed intervals for generating an error signal proportional to the difference in frequency between said signal and said predetermined frequency, and means responsive to the error signal during other fixed intervals for sorting said sources into "good" or "reject" containers depending upon the magnitude of said error signal.
